SHARPENING OF ENDLESS KNIFE BANDS

William Hoppe, Longmeadow, and Lawrence W. Schoppee, Springfield, Mass., assignors to Package Machinery Company, East Longmeadow, Mass., a corporation of Massachusetts

Filed Nov. 5, 1958, Ser. No. 772,081

6 Claims. (Cl. 51—250)

The present invention relates to the sharpening of knives and the like and more particularly is directed to improvements in sharpening endless knife bands or blades.

The environment of the present invention is best demonstrated by one type of slicing machine which finds widespread application in the slicing of loaves of bread. This slicing machine comprises a series of endless knife blades carried by a pair of rotating drums and generally twisted 180° into a figure 8 configuration, thereby providing a slicing zone comprising a plurality of generally parallel knife portions through which a loaf of bread may be advanced in the slicing operation.

The cutting edge of each of these knife bands is preferably serrated or scalloped for greater slicing efficiency, particularly in the case of soft articles such as bread. Whether scalloped or not, the sharpening of these knife bands is a problem of some consequence in that the great number of blades involved and their lack of accessibility on most machines, involves a substantial amount of down time of the machine for the sharpening operation. The relatively lengthy down time is primarily due to the fact that each blade is individually sharpened by a skilled workman, in most all instances.

Conventional manual sharpening of these knife bands involves other disadvantages in that the blades are sharpened varying amounts instead of uniformly. Also, in the case of scalloped cutting edges, conventional sharpening techniques tend to destroy the pointed edges provided by the scalloped pattern and progressively reduce the cutting efficiency of the knife band each time it is sharpened. In addition to this, the conventional hand operation of sharpening the blades involves a considerable risk of serious injury to the workmen sharpening the rapidly moving and closely spaced blades.

All of these factors combine to deter sharpening of the blades of such slicing machines as frequently as is necessary or desirable so that the bands do not slice the articles as efficiently as is possible.

These problems have not gone unnoticed in the prior art, nonetheless, prior to the present invention, such sharpening operations have by and large, if not exclusively been done by hand with each blade being sharpened individually in order to get the desired result.

The overall object of the invention is to provide an improved method and means for simultaneously sharpening a series of endless knife bands in a simple, accurate and economical manner thereby minimizing the time required for the sharpening operation and encouraging maximum slicing efficiency at all times.

A further object of the invention is to minimize, if not eliminate, any physical hazard to workmen in the sharpening of endless knife bands.

Yet another object of the invention is to provide for the sharpening of serrated or scalloped endless knife bands in a manner preserving the high points characterizing this type of blade.

The above and other related objects and features of the invention, including the various novel features thereof, will be apparent from a reading of the following description of the disclosure found in the accompanying drawings and the novelty thereof pointed out in the appended claims.

FIG. 1 is a diagrammatical side elevation of the type of

2

slicing machine referred to above showing the relationship of the improved sharpening apparatus thereto;

FIG. 2 is an elevation of the sharpening apparatus indicated in FIG. 1, with only the upper drum and blades of the slicing machine being shown;

FIG. 3 is a section taken along the line III—III in FIG. 2 showing one unit of the sharpening apparatus in its rest position;

FIG. 4 is a section, on an enlarged scale, taken on line IV—IV of FIG. 3 showing the operation of a ratcheting device for the sharpening stone;

FIG. 5 is a view taken in the direction of arrow A in FIG. 4;

FIG. 6 is a section taken on line VI—VI in FIG. 2 showing the other unit of the sharpening apparatus in its rest position;

FIG. 7 is a fragmentary view on a greatly enlarged scale illustrating the sharpening operation; and

FIG. 8 is a fragmentary view of one of the blades of the slicing machine.

Reference is first made to FIG. 1 showing one design of a slicing machine having a series of endless knife bands or blades 10. The slicing machine comprises a pair of side frames 11 on which most of the various parts of the machine are mounted. The blades 10 pass around an upper rotatable drum 12, are twisted 180° and then pass around a lower drum 14, and are then twisted 180° as they extend upwardly again to the drum 12 forming a figure 8. The drums 12 and 14 are spaced apart a distance sufficient to tension the bands 10 and maintain them taut. Drum 14 is continuously rotated at a relatively high rate to advance the blades 10 through the slicing zone, intermediate the drums 12 and 14 at a speed sufficient for effective cutting operation. In this zone the blades 10 are parallel and transversely spaced for the thickness desired in slicing the bread. Loaves of bread are advanced along a platform 16 and then down a ramp 15 through the slicing zone, after which it is common practice to automatically transfer the sliced loaves to a wrapping machine.

Also from FIG. 1 the relative disposition of the sharpening apparatus of the present invention may be seen. This apparatus comprises an upper unit 17 for sharpening one side of the cutting edge of each blade 10 and a lower unit 18 for sharpening the other side of these cutting edges.

FIG. 2 more specifically illustrates the relationship of the sharpening units 17 and 18 to the blades 10 as they pass around the drum 12. The sharpening units 17 and 18 respectively comprise honing or abrading members 19 and 20 which are carried by novel apparatus, to be described shortly, for controlled movement in sharpening the blades 10. More specifically, the honing member 19 is brought into and out of simultaneous engagement with all the blades 10 along a line where the angle of twist of the blades approximates the desired angle of the beveled cutting edge. This manipulation of the honing member 19 sharpens one side of the cutting edge of each of the moving blades 10. The honing member 20 is similarly brought into and out of engagement with the moving blades 10 to sharpen the other side of the cutting edges. The member 20 is preferably disposed to engage the blades 10 on the opposite side of the drum 12 so that both sides of the cutting edges will be beveled on the same angle.

The constructional details of the sharpening units 17 and 18 will now be described along with a description of their novel relationships in sharpening the blades 10 in accordance with the improved method taught herein.

Referring now to FIGS. 2 and 3 the hone 19 of the upper unit 17 comprises a series of cylindrical abrading members or stones 21 formed of aluminum oxide, or silicon carbide or the like, mounted on a shaft 22 and axially positioned thereon by nuts 23. The hone 19 is

carried by a parallel linkage arrangement which includes at the right end of the shaft 22 a block 24 (FIG. 3) rotatably receiving one end of the shaft 22. The block 24 has an outwardly extending pin 26 which is pivotally received by the lower end of a link 28, the link 28 being maintained on the pin 26 by a locking collar 30. The upper end of the link 28 is pivotally mounted on a stud 32 extending from a block 34 and maintained thereon by a locking collar 36. The block 34 is secured, as by set screws, to a fixed cross shaft 38 which is secured at each end to the side frames 11 as by the illustrated mounting pads 42.

At this point, note will be taken of the fact that in the following description reference will be made to several locking or retaining collars such as the collars 30 and 36. Each of these collars is secured to the pin or stud on which it is mounted by a set screw or the like without specific reference being made to such fasteners as the description proceeds.

The left hand end of the shaft 22 (FIG. 3) is rotatably received by a block 44 and is axially positioned thereon by a snap ring 46 and a locking collar 48. The block 44 has an outwardly extending pin 50 which is pivotally received by the lower end of a link 52 (see also FIG. 2) with a locking collar 53 holding the link 52 in place. The upper end of link 52 is pivotally mounted on a pin 54 which extends from a fixed block 56 and is maintained thereon by locking collars 55 at each end. The block 56, like the block 34, is also secured to the cross shaft 38 as by the illustrated set screws.

The center distances (FIG. 3) between the pins 32 and 26 and 54 and 50 are equal and likewise the center distances between the pins 54 and 32 and 50 and 26 are also equal, thus defining a parallel linkage for moving the hone 19 into and out of sharpening engagement with the blades 10. Such movement of the hone 19 may be readily obtained by oscillating one of the short links (52 or 28) of the described parallel linkage.

This end may be advantageously attained by means of a removable handle or lever 58 (FIGS. 2 and 3) which is slotted at 60 (FIG. 3) to pass over fixed pins 62 and 64 projecting from the link 52 as well as the pin 54. It will also be noted that collars 66 on the pins 62 and 64, as well as the collar 55, are spaced from the link 52 (FIG. 2) a distance slightly greater than the thickness of the handle 58 to facilitate its being positioned to swing the hone 19 into and out of sharpening engagement with the blades 10.

Though not shown in detail, a panel member extends between the side frames 11 (FIG. 1) overlying the sharpening unit 17. This panel is slotted to permit the removable handle 58 to be positioned for the sharpening operation without exposing the workman to the hazard of the moving blades 10. The handle 58 in its operating position extends beyond the outline of the frames 11 so the workman may sharpen the blades while standing beside the slicing machine.

Referring back to the fixed cross shaft 38 (FIG. 3) it will be seen that a further block 68 is secured thereto with a spring pin 70 extending therefrom and angled forwardly of the hone 19 (see also FIG. 4). One end of a tension spring 72 is secured to the pin 70 while its other end is caught by a spring pin 74 threaded into the collar 30 and also serving as a set screw for the collar 30. The spring 72 urges the hone 19 toward the left to a position limited by contact of the shaft 22 with the side frame 11 wherein the hone is out of contact with the blades 10 and in a rest position.

From the above description, it has been brought out that the cylindrical hone 19 is brought into and out of sharpening engagement with the moving blades 10. Essentially there is line contact between the blades 10 and the hone 19 which is advantageous for reasons later developed in greater detail. In order that the hone 19 does not become flattened and this line contact lost, means

are provided for rotating the hone 19 an incremental amount each time the lever 58 is oscillated. These means (FIGS. 3, 4, and 5) include a ratchet wheel 76 which is held fast upon the shaft 22 by a set screw threaded into its hub 78. A pawl 80 is secured to the link 28. As the link 28 swings in a counterclockwise direction from its rest position of FIG. 3, the pawl 80 swings downwardly and an inturned lip 82 thereof engages one of the teeth on ratchet wheel 76 as can be best appreciated from FIGS. 4 and 5 wherein the link 28 has been swung to an extreme counterclockwise position. The hone 19 is thus rotated in a clockwise direction (FIG. 4) each time the handle 58 is swung to in a counterclockwise direction as limited by engagement of the shaft 22 with the right hand side frame 11 (FIG. 5). In this manner the peripheral surface of the hone 19 is successively brought into sharpening or honing contact with the blades 10 thus maintaining, or tending to maintain at all times a smooth, cylindrical sharpening surface.

In passing, it will be noted that the shaft 22 is axially fixed relative to the block 24 by the ratchet wheel hub 78 and a snap ring 79. A keeper spring 84 is secured to the block 24 by screw 86 and is provided with an inturned lip 88 (FIG. 4) which engages successive teeth of the ratchet wheel 76. In this manner reverse or counterclockwise (FIG. 4) rotation of the ratchet wheel is prevented when the link 28 swings in a clockwise (FIG. 5) direction back to the rest position illustrated in FIG. 3 and in so doing drags the pawl 80 upwardly over the teeth of wheel 76. The keeper spring 84 also serves to prevent the hone 19 from being rotated by the blades 10. That is, when the hone 19 is brought into engagement with the moving blades 10 (FIG. 2) there is a force or drag tending to rotate the hone in a counterclockwise direction. Such counterclockwise rotation is, however, prevented by the keeper 84.

The lower sharpening unit is similar in construction to the upper unit 19 just described. The principal difference between the two is in the provisions made for disposing the honing member 20 inside of the loops of the endless band knives 10 to sharpen the opposite side of each cutting edge. Referring now to FIGS. 2 and 6 and particularly the latter, the hone 20 is compositely formed by a plurality of abrading stones 20' held fast on a shaft 105 by nuts 103. The hone 20 is supported from a cross shaft 90 secured at each end to the slicing machine frames 11 as by mounting pads 89. Blocks 91 and 92 are secured to the shaft 90 adjacent the side frames 11 by the illustrated set screws. Brackets 93 (see also FIG. 2) and 94 are secured as by welding, to the blocks 91 and 92 respectively and extend upwardly therefrom to receive pins 95 and 96 which in turn pivotally support the bossed upper ends of links 98 and 100. One end of each of the pins 95 and 96 has an enlarged head portion engaged with the links 98 and 100 with the other ends of the pins 95 and 96 being held in place by lock collars 97 (FIG. 2). Blocks 102 and 104 rotatably receive the ends of the shaft 105, of the hone 20 and integral pins 106 and 108 extend rearwardly from these blocks and are pivotally received by the links 98 and 100. Lock collars 107 retain the pins 106 and 108 in place on the links 98 and 100.

A tie rod 109 is pivotally connected at one end to the link 100 by a pin 110 and at the other end to a small connecting link 112 by a pin 111 (FIG. 6). One end of an actuating link 114 is also pivotally disposed on the pin 111 intermediate the rod 109 and link 112. The pin 111 is headed on one end and held in place by a lock nut 113 (FIG. 2) threaded onto its other end. The other end of the connecting link 112 is pivotally connected to the lower end of link 98 by a headed pin 115 having a locking collar 115'. The lower end of the link 114 is pivotally mounted on a pin 119 which extends through the block 91 with locking collars 120 and 121 secured to its ends, the collar 121 being spaced from the link

114 (FIG. 6). An operating lever or handle 116 is slotted as at 117 to receive the pins 119 and a fixed pin 118 projecting from the link 114 and is held in place on the link 114 by collars 113' and 121 spaced therefrom. The pin 119, it will be seen, provides a fulcrum about which link 114 is rotated by handle 116.

The center spacing between the pins 95 and 106 (FIG. 6) is equal to the center spacing between the pins 96 and 108 and the center spacing between the pins 95 and 96 is equal to that between the pins 106 and 108. This defines a parallel linkage which may be actuated by the lever 116 to carry the hone 20 into parallel engagement with all the knife bands 10. At this point note will be taken of the fact that the hone shaft 105 is axially fixed with respect to the left hand block 102 by means of a snap ring 123 and the hub of a pawl 126, while the right hand end of the shaft 105 is not axially fixed with respect to the block 104. This arrangement is for purposes later discussed. However, the described parallel relationship is at least substantially at all times maintained by the link 112 and the connecting rod 109 and the angular relationships thereof with the links 98 and 100.

The hone 20 is rotated about its axis in essentially the same fashion as the hone 19 to provide for even wear of the cylindrical hone surface. A pawl 124 is secured on the link 98 (FIGS. 2 and 6) and is engageable with ratchet wheel 126 secured to the hone shaft 105. Each time the hone 20 is moved to its left hand position (FIG. 6) a lip 125 (FIG. 2) on the free end of pawl 124 is swung downwardly into engagement with one of the teeth on ratchet wheel 126 thereby rotating the shaft 105 to bring successive portions of the stones 20' into sharpening relation with the bands 10. A keeper spring 127 is secured to the block 102 by a screw 129 and extends into engagement with the teeth of the ratchet 126 preventing its reverse rotation by the pawl 124 or the moving blades 10.

The hone 20 is normally maintained in the rest position shown in FIG. 6 by a coil spring 128 which is secured at one end to the outer end of link 100 and at its other end to an arm 130 projecting from a collar 131 secured to shaft 90. The spring 128, it will be seen, functions to return the hone 20 to its normal or rest position, disengaged from the bands 10, whenever the handle 116 is released by the operator. Thus also, there is at all times a force tending to bring the hone 20 out of engagement with the bands 10, thereby minimizing the possibility of the operator maintaining the hone in engagement with the blades 10 long enough to remove an excessive amount of metal from the bands.

For efficient operation of slicing machines of the type herein referred to, continuous operation with a minimum of down time is essential. Not only does the sharpening apparatus of the present invention minimize or eliminate down time for the sharpening operation, but also provision is made for facilitating replacement of the bands 10. Such provision is required by reason of the preferred mounting of the hone 20 within the loops formed by the knife bands 10 with the cross connection, i.e. the link 112 and rod 109, between the links 98 and 100 disposed outside of the knife band loops. The hone 20 is therefore disassociable from its parallel linkage mounting. Thus it will be seen that one end of the shaft 105 is received by an upwardly open journal formed in the block 102. The block 102 is slotted intermediate its length to receive a retaining spring 135 which is secured in place by a screw 133 with its free, curved end holding the shaft 105 seated on the open journal. Thus the left hand end of shaft 105 may be pivoted about pin 108 and dissociated from the link 98 and the right hand end of shaft 105 withdrawn from block 104 to allow new bands 10 to be slipped into place. The links 98 and 100 are maintained in the described parallel relationship by the tie rod 109 and link 112 when the hone 20 is thus removed so that it may be readily replaced once new bands 10 have been positioned.

Operation

The sharpening units 17 and 18 are functionally identical in their use in sharpening the blades 10. That is, in the preferred embodiment, above-described, for sharpening knife bands on both sides of their cutting edges, the relative disposition of the hones 19 and 20 to the blades 10 is identical save for the fact that the hone 19 is effective to sharpen one side of the cutting edges while the hone 20 is effective to sharpen the other side of the cutting edges.

For simplicity, it will be necessary to describe only the sharpening action of the lower unit 18. One of the advantages of the present invention is to be found in the highly effective manner in which blades having scalloped cutting edges are sharpened both on their high points and their low points. The scalloped cutting edges of the blades 10 is best illustrated in FIG. 8 wherein it can be seen that the blade 10 comprises spaced high points 10a with relieved or low points 10b therebetween.

With this in mind and from FIG. 7, it can be seen that the beveled surfaces on each side of the cutting edge of the blades do not lie in precisely the same planes, though for purposes of reference in the present invention this discrepancy will be neglected. Thus from FIGS. 2 and 6 it will be seen that the hone 20 is moved into engagement with the bands 10 along a line *l* which is disposed at substantially the same angle to all of the blades 10, which angle approximates the desired bevel angle *c* (FIG. 7) for the cutting edges of the blades. This relationship is preferably gained by reason of bringing the hone 20 into engagement with the bands 10 along a line (the line *l*) parallel to the line of tangency of the bands with the drum 12 and spaced therefrom a distance such that the twist of the bands 10 forms the angle *c*, the bands 10 being further twisted therebeyond into parallel relationship in the slicing zone.

The parallel linkage for moving the hone 20 into engagement with the bands 10 insures simultaneous engagement with all of the bands (neglecting the existence of high points 10a mentioned above). The convex cylindrical shape of the abrading or band engaging surface of hone 20 is instrumental in sharpening both the high points 10a and low points 10b to preserve the scalloped cutting edges of the knife bands. This end is best appreciated by noting that the hone 20 is moved into engagement with the bands 10 a distance sufficient to contact the low points 10b (FIG. 7). The high points 10a are then further deflected downwardly as the bands move past the hone 20. The hone 20 is purposely made on a radius sufficiently small so that the hone does not span the high points 10a. Further the natural resilience of the tensioned bands urges the low points 10b into engagement with the hone 20 with approximately the same force as the high points 10a so that in the sharpening operation approximately the same amount of metal is removed from the high and low points. Thus the blades 10 are sharpened and their scalloped cutting edges preserved.

By disposing the units 17 and 18 on opposite sides of the drum 12, it is possible to obtain the same relationships between the hone 19 and bands 10 for sharpening both sides of the cutting edges of the bands. The sharpening operation requires very little time because of the high speed at which the bands are moving. The removable handles 58 and 116 (FIGS. 1 and 2), (a common handle 65 may be used) are simply connected to the parallel linkages and oscillated a few times to obtain the necessary sharpening or dressing of the cutting edges of the bands 10.

While the present disclosure is based on manual operation of the hones 19 and 20, it is recognized that certain advantages could be obtained by employing automatic or semi-automatic means for bringing these hones into and out of sharpening engagement with the knife bands. Thus, for example, an electric motor drive could readily be provided to swing the parallel linkage for each hone in the same manner as the described hand operation. An actuator

ing switch for this electric drive would be mounted for ready accessibility and convenience on the exterior of the slicing machine or at any remote point desired. Preferably means would be provided for limiting operation of the electric drive to a predetermined time which would be sufficient for the blades to be sharpened without excessive removal of material. This end could be attained by using a time limit switch which would energize the electric drive for the honers for the desired length of time and then automatically open to deenergize the circuit for the electric drive. Such an arrangement would have the advantage of further eliminating the human factor in the sharpening of endless knife bands and thus insure uniform sharpening of the blades at all times.

Having thus described the invention what is claimed as novel and desired to be secured by Letters Patent of the United States is:

1. An apparatus for sharpening a plurality of moving knife bands trained around a pair of spaced rotating drums and twisted into a parallel relationship to provide a slicing zone intermediate said drums, said apparatus comprising a cylindrical honing member disposed adjacent one of said drums and spanning one run of said bands to one side thereof, the axis of said cylindrical member being disposed parallel to the axis of said adjacent drum, means for moving said honing member into and out of simultaneous engagement with the bevelled surface of the cutting edge of each moving band, and means responsive to said moving means for rotating said honing member about its axis to insure even wear of the cylindrical surface thereof.

2. Apparatus for sharpening a plurality of moving knife bands trained around a pair of spaced rotating drums and twisted into parallel relationship to provide a slicing zone intermediate said drums, said apparatus comprising an elongated cylindrical honing member spanning one run of the bands adjacent one of said drums and means for moving said honing member into and out of simultaneous engagement with all of said moving bands along a line disposed at substantially the same angle to all of the bands and spaced from the line of tangency of the run of bands with the adjacent drum a distance such that the bands are disposed relative to said line at approximately the desired bevel angle for the cutting edges of the bands, the means for moving said honing member comprising a parallel linkage arrangement having pivotal connections with the ends of the honing member whereby the honing member is brought into and out of engagement with the bands and in a direction having components both transversely and longitudinally of the axis of the adjacent drum.

3. An apparatus for sharpening a plurality of moving knife bands trained under tension around a pair of spaced rotating drums and twisted into a parallel relationship to provide a slicing zone intermediate said drums, said apparatus comprising a honing member including a shaft mounted adjacent one of said drums with its axis parallel to the axis of said one drum and having a cylindrical honing surface formed coaxially of the axis of said shaft and disposed in spaced opposing relation with one run of said bands, means including a manually operable parallel linkage for moving said honing member, and particularly the

honing surface thereof into and out of engagement with said bands along a line spaced from the line of tangency of the bands with said one drum a distance at which the bands are twisted to a predetermined angle with respect to said honing surface which angle approximates the desired bevel angle of the cutting edges of the bands whereby said tensioned bands will be engaged by said honing surface as they are displaced to an angular relationship therewith more precisely equal to the desired beveled angle, and means for rotating the honing member in response to movement of the parallel linkage means in order to assure even wear of the cylindrical surface of the honing member.

4. Apparatus as in claim 3 wherein a removable handle projecting outwardly of said bands is provided for actuating the parallel linkage arrangement and wherein further there is provided spring means effective upon said parallel linkage for maintaining the honing member out of engagement with said bands.

5. Apparatus for sharpening both sides of a plurality of moving knife bands trained in loops around a pair of spaced rotating drums and twisted into a parallel relationship to provide a slicing zone intermediate said drums, said apparatus comprising a first unit including a cylindrical honing member disposed exteriorly of said loop adjacent one of said drums and spanning a run of said bands, said member having abrading surface portions disposed in spaced opposed relation to said bands, parallel linkage means for supporting and moving said honing member towards and into engagement with said bands with the abrading surface portions thereof engaging the beveled surface on one side of the cutting edge of each moving band and a second sharpening unit including a second cylindrical honing member disposed interiorly of said loops adjacent one of said drums and spanning a run of said bands, said second member having abrading surface portions disposed in spaced opposed relation to said bands and parallel linkage means for supporting and moving said second honing member towards and into engagement with said bands with the abrading surface portions thereof engaging the beveled surface of the other side of the cutting edge of each moving band, at least one end of the second honing member being detachably secured to the parallel linkage means therefor.

6. Apparatus as in claim 5 wherein the parallel linkage means of the second unit includes a tie rod disposed outside the band loops and maintaining the linkage in parallelism.
